CALENDAR

Adeline C. Wesseler, Los Angeles, Calif.

Application August 28, 1945, Serial No. 613,080

2 Claims. (Cl. 40—117)

1

This invention relates to a calendar and has as its primary object provision of a weekly calendar which is adapted to be adjusted to conform to the particular date of the days of the month applicable to the days of the week displayed on the calendar.

A particular object of the invention is to provide adjustment means for compensating for the difference in the numbers of days in the various months so that a correct daily reading may be had of weeks embracing the last day or days of one month and the first day or days of a succeeding month.

A further object is to provide a calendar of the above character in which the parts are so formed and arranged as to be economically constructed and assembled.

With the foregoing objects in view, together with such other objects and advantages as may subsequently appear, the invention resides in the parts and in the combination, construction and arrangement of parts hereinafter described and claimed, and illustrated by way of example in the accompanying drawing, in which:

Fig. 1 is a view of the calendar as seen in front elevation;

Fig. 2 is a detail in horizontal section taken on the line 2—2 of Fig. 1;

Fig. 3 is a view in side elevation;

Fig. 4 is a view in front elevation of a fragmentary portion of the date ribbon showing the date adjusting means in one position thereon;

Fig. 5 is a view similar to Fig. 4 showing the date adjusting means in another of its positions;

Fig. 6 is an enlarged sectional view and perspective taken on the line 6—6 of Fig. 5 depicting the construction of the date adjusting means.

Generally this invention consists of a calendar including a panel bearing the names of the days of the week arranged in a column together with a ribbon bearing the numbers of the days of the month arranged so as to be associated with the day column, and including means for winding the ribbon to position a selected group of numbers in such relation to the names of the days of the week as to be readable therewith in designating a week of dates.

Referring to the drawings more specifically, A indicates generally a panel on which is arranged the names of the days of a week disposed in a column in their consecutive order commencing with "Sunday" and reading downwardly and ending in "Saturday" as shown in Fig. 1. The panel A is formed with vertically spaced openings 7 and 8 and turnably mounted on the panel and extending transversely

2

thereof across the openings 7 and 8 are spindles 9 and 10 on which are wound and secured the end portions of a ribbon B a portion of which overlies the outer face of the panel A alongside and parallel to the column of the designated days of the week.

As a means for journaling the spindles 9 and 10 on the panel A, the latter is provided with a backing sheet 13 formed with bends 13' to 10 overlie the spindles 9 and 10 and form bearings for the latter; the backing sheet 13 being suitably fastened to the back portion of the panel as by means of an adhesive and in a fashion to maintain the spindles 9 and 10 in place.

15 The ribbon B is formed in two sections C and D, the section C bearing on its outer face a column of numbers representing the days of a month from 1 to 31 inclusive, and the section D which connects with the length of ribbon C 20 bearing on its face a series of numerals commencing with the numeral 1. This second section of ribbon D carries any desired numbers in numerical order but preferably carries not more than six of such numbers since the purpose of 25 this second section of ribbon is to provide at least one date following the last day of the month indicated on the leading length of the ribbon.

The numbers are spaced on the ribbon so that 30 when a number is aligned with one of the designations of the day of the week on the panel A the remaining exposed numbers will align with the other designations of the days of the week as indicated in Fig. 1.

The above recited structure constitutes a 35 weekly calendar since on manipulating the ribbon by winding it from one spindle to the other a number corresponding to a particular date falling on Sunday, on being positioned opposite the word "Sunday" the dates of the remaining 40 days of the week will be indicated in their order.

As a means for rendering the calendar readable throughout a particular month, the panel A is fitted with a series of superimposed flexible strips E which strips bear the names of the 45 months of the year, together with a designation of the number of days in the indicated month. These strips E may be supported in any suitable fashion on the panel A but are here shown as having their ends extended through 50 and supported in openings 11 and 12 formed in the upper marginal portion of the panel.

An important feature of the invention resides in the provision of a means for adjusting the leading portion C of the ribbon B so that the 55 last date indicated on the leading section will correspond to the number of days of a month

indicated on a strip E. Normally the last number on the leading portion C of the ribbon will be 31 as shown in Fig. 4 to accommodate the ribbon to the months containing thirty-one days, namely, January, March, May, July, August, October and December. In order to shorten the exposed area of the leading ribbon section C, a take-up F is provided embodying a slide 14 having a pair of parallel slots a and b separated by a bar c; the slots a and b being flanked by side bars d and e. The take-up F also includes a link 15 having parallel side bars f and g. The outer end portion of the lead ribbon section C is passed through the slots a and b of the slide F to overlie the bar c, and underlie the bars d and e and is then passed through the link 15 around the bar f, then returned upon itself as shown in Fig. 6, the end of the ribbon being attached to the bar c of the slide 14 as indicated at 16. The outer end of the other ribbon section D is affixed to the bar g of the link 15 as shown in Fig. 6 at 17.

In order to facilitate winding the members 14 and 15 into the roll formed by the ribbon, such members are made quite thin and as small as practicable and are also curved in the direction of the length of the ribbon so as to conform to the curvature of the portion of the ribbon windings engaged thereby.

When it is desired to vary the length of the lead ribbon section C the ribbon B is unwound from the spindles 9 and 10 to expose the members 14 and 15, and the member 14 is shifted lengthwise on the ribbon to bring the desired number thereon contiguous to the member 15; the portion of the ribbon taken up or fed out passes through the member 15. In this fashion the dates on the ribbon may be terminated according to the last day or the number of days in the month selected. For example, the ribbon may be taken up to conceal the date numbers 29, 30 and 31 and expose the number 28 next to the link 15 to designate the number of days in February, or to expose the number 29 as shown in Fig. 5 as when February has twenty-nine days in leap year. In like fashion the last number may be 30 in accordance with the number of days in April, June, September and November.

In the operation of the invention, having selected the particular month and week of the month to be indicated on the calendar, the date-bearing ribbon is adjusted as above described to indicate at the end of the first ribbon section C the number of days of the selected month, whereupon the spindles 9 and 10 are manipulated to wind the ribbon to a position where the exposed group of numbers thereon will align with the names of the days of the week according to the dates thereof. In the example shown in the drawings, the month of January has been selected which has thirty-one days, in which instance the numbered ribbon will be adjusted so that the first section C thereof will end in the number 31 as shown in Fig. 4. Assuming that the first day of January falls on Sunday the ribbon will then be wound on the spindle 10 until the number "1" on the ribbon section C will align with the word "Sunday" thus positioning the proper dates in consecutive order in line with the designations "Monday," "Tuesday," "Wednesday," "Thursday," "Friday" and "Saturday." At the end of the designated week the spindle 9 will be manipulated to wind the ribbon thereon to position the number "8" in line with the word "Sunday."

This operation is repeated until the last week in the month which in the examples given would occur on the 29th. The calendar would then read "Sunday—29; Monday—30; Tuesday—31." The number "1" on the second section D of the ribbon would then align with the word "Wednesday" to designate the first of the succeeding month of February. When this date is reached it is desirable to adjust the length of the ribbon according to the number of days in February so that the last date will appear immediately before the number "1" on the second section of the ribbon. On this adjustment being completed the ribbon is rewound on the spindle 10 until the number "1" on the first section thereof is opposite or in line with the word "Wednesday."

When the calendar is changed according to changes in the month, the proper strip E is placed outermost in the stack thereof into position to be read from the front of the calendar. By provision of the data on the month designating strips a person not knowing the number of days in a particular month can be advised thereof on referring to the data on the strips.

I claim:

1. In a calendar, a ribbon embodying a first section carrying a row of numbers from 1 to 31 inclusive, and a second section bearing at least the numeral "1"; a link to which the second section is attached contiguous the number "1" thereon and through which an end portion of the first section is looped to form a looped end, a slide on the first section slidable thereon to which the loop end of the first section is affixed, a pair of spaced spindles bearing said ribbon on which the ribbon may be wound from either spindle, a panel, means for turnably supporting said spindles on said panel in spaced relation to each other with a length of said ribbon overlying the front of said panel, and indicia on said panel designating the days of the week with which exposed numbers on said ribbon may be aligned.

2. In a calendar, a panel bearing the names of the days of the week, a ribbon provided with a row of numerals representing the days of the month, a pair of spaced spindles journaled on said panel on which spindles said ribbon is mounted to be wound from either spindle to the other, said ribbon being positioned relative to the names of the days of the week on the panel to align a group of the numbers thereon in numerical order in line with the designated days of the week, said ribbon being formed in two sections with the numbers on one of said sections reading from 1 to 31 inclusive, the second section being connected to the first section and bearing at least the number "1" arranged contiguous and spaced from the number "31" on the other section; and take-up means including the connection between the two ribbon sections whereby the first ribbon section may be adjusted to vary the number exposed at the end portion thereof contiguous the number "1" of the other section.

ADELINE C. WESSELER.
